(57) **CLAIM**

The ornamental design for a reflective lighting fixture, as shown and described.

DESCRIPTION

FIG. 1 is a front perspective view of a reflective lighting fixture according to our new design.

FIG. 2 is a top view of the reflective lighting fixture of FIG. 1.

FIG. 3 is a bottom view of the reflective lighting fixture of FIG. 1. The bottom panel is transparent or translucent, and structures visible through the transparent or translucent bottom panel are depicted.

FIG. 4 is a front view of the reflective lighting fixture of FIG. 1.

FIG. 5 is a rear view of the reflective lighting fixture of FIG. 1.

FIG. 6 is a right side view of the reflective lighting fixture of FIG. 1. The left side view is a mirror image of the right side view; and,

FIG. 7 is a right side perspective view of the reflective lighting fixture of FIG. 1.
